UNITED STATES PATENT OFFICE

162,040

GOWN

Elizabeth Kay, Brooklyn, N. Y.

Application April 28, 1950, Serial No. 9,559

Term of patent 3½ years

(Cl. D3—26)

To all whom it may concern:

Be it known that I, Elizabeth Kay, a citizen of the United States, residing at Brooklyn, New York, in the county of Kings and State of New York, have invented a new, original, and ornamental Design for a Gown, of which the following is a specification, reference being had to the accompanying drawing, forming part thereof.

In the drawing:

Fig. 1 is a front elevational view of a gown, showing my new design;

Fig. 2 is a rear elevational view; and

Fig. 3 is a side elevational view of the same.

I claim:

The ornamental design for a gown, as shown.

ELIZABETH KAY.
